UNITED STATES PATENT OFFICE.

JOSEPH M. WEST, OF ROCKPORT, MISSOURI.

AMUSEMENT DEVICE.

1,079,678.

Specification of Letters Patent. Patented Nov. 25, 1913.

Application filed May 14, 1913. Serial No. 767,687.

To all whom it may concern:

Be it known that I, JOSEPH M. WEST, a citizen of the United States, residing at Rockport, in the county of Atchison and 5 State of Missouri, have invented a new and useful Amusement Device, of which the following is a specification.

The present invention relates to improvements in amusement devices, the present device being constructed so that flexible targets thereof are adapted to be struck by a thrown object, as for instance a ball, one object of the invention being the provision of means for resiliently holding the targets to 10 be struck by the ball in projected position, and a means for resetting such targets after the same have been released due to being struck.

A further object of the invention is the 20 provision of an amusement device of the present character, in which an annulus carries a plurality of radially disposed flexible targets, rearwardly held to form the radii of the annulus with the free ends toward the 25 center thereof, whereby when such free ends or any portion of such hinged targets are struck by a thrown object, as for instance a ball, the same will be released and moved rearwardly, there being further provided 30 means for returning such flexible targets to the proper forward and locked position, and means for returning the thrown ball to the player.

With the foregoing and other objects in 35 view which will appear as the description proceeds, the invention resides in the combination and arrangement of parts and in the details of description hereinafter described and claimed, it being understood 40 that changes in the precise embodiment of the invention herein disclosed can be made within the scope of what is claimed without departing from the spirit of the invention.

In the drawings—Figure 1 is a front elevation of the complete device. Fig. 2 is a 45 top plan view with the protecting screens removed. Fig. 3 is a longitudinal sectional view with the screens in position. Figs. 4 and 5 are detail views of the mounting of 50 the flexible members.

Referring to the drawings, the numeral 1 designates the main frame of the machine, which is supported upon legs or other supports 2, and has upstanding at the forward 55 end a plate 3, which has its upper edge recessed to receive and have secured thereto

by screws or other means the cylindrical band or ring 4. The ring 4 constitutes a means for properly supporting through the hinges 5, a plurality of arms or targets 6, 60 which when properly positioned, as clearly shown in Fig. 1, form the radii for the member 4, with the reduced points 7 terminating concentrically of the member 4.

In order to provide a means for locking 65 the targets or arms 6, so that their outer face is at right angles to the axis of the member 4, the strap 8 provided with a resilient locking tongue 9 is provided, one for each of the arms or targets 6. When in 70 locking engagement the same assumes the position as clearly shown in Figs. 4 and 5.

Connected to the outer surface of the member 4 and projecting forwardly therefrom, are a plurality of brackets 10, which 75 carry the disk or ring 11, which is of greater diameter than the ring 4 and the outer face of which is padded as at 12. The ring 11 therefore provides means to receive any "wild" balls that may be thrown. Connected to the member 11 and extending forwardly thereof, are the arms 13, which constitute a support for the wire cage 14. This cage is so disposed as to prevent any "wild" 80 balls, from passing beyond the device and also for guiding the same as they fall into the hopper 19, as will presently appear.

Extending rearwardly from the upper periphery 4 and incasing the frame of the device, is the rear cage 15. 90

Mounted in the frame 1 are the ball chutes 16 and 17, which lead and direct the balls after passage through the annular member 4 through the opening or slot 18 into the collecting hopper 19, whose outlet 20 is disposed to return the balls to the forward part of the device and to the position from which the player stands to throw the ball. 95

As the arm or targets 6 are biased to incline, as shown at the bottom of Fig. 3, the extreme end thereof must be so positioned as to permit of the ready setting of the same when it is desired to place the targets in the proper position to receive the balls thrown. In order to accomplish this, the 100 bar 21 is mounted transversely of the frame 1 for movement to and from the supporting member 4. Connected to this bar intermediate of its ends and upstanding therefrom is a vertical post 22, which carries the divergent arms 23 which support the target setting ring 24. This ring as 110

clearly illustrated is disposed so that when in its rearmost position, the extreme inner or free ends of the arms or targets 6 when released and knocked inwardly due to being struck by a thrown ball, will engage the ring 24 so that when the post or standard 22 is moved forwardly, the targets 6 will all simultaneously be reset and placed in target position by the members 9, as clearly illustrated in Fig. 5.

In order to properly slide the bar 21 and the resetting ring 24, the two links 25 are connected to the bar 21 centrally thereof adjacent the connection of the post 22 thereto. The links 25 are pivoted centrally and to the auxiliary operating lever 26, which is pivoted to the arm 27 carried by one side of the main frame 1. Connected to the free end of the auxiliary lever 26 is a link 28, which is extended forwardly and connected to the main operating lever 29. This lever 29 is disposed exteriorly of the cage 14 or in ready access to the attendant of the present amusement device.

Where the term arm has been employed, throughout the present description, the same will be construed to mean a target, as each one of the respective arms 6 are targets, radially disposed for movement into and out of a position at right angles to the access of the supporting member 4.

What is claimed is:

1. An amusement device, including a vertically disposed cylindrical member, a plurality of targets hingedly connected thereto and disposed to form radii for the member, a resilient lock for each target for maintaining the target at right angles to the axis of the supporting member, means for resetting the targets, such means including a ring disposed to be in alignment to receive any or all of the targets when inclined after being struck, and means for moving the ring to place the targets simultaneously in set position.

2. An amusement device, including a frame, a cylindrical member carried by the frame extending in a vertical position, a plurality of targets hinged to the cylindrical member with their free ends extended inwardly toward the center thereof, said targets being disposed as the radii of the cy-

lindrical member, means for locking each target in radial relation, and means disposed in the rear to receive the inclined targets.

3. An amusement device, including a frame, a cylindrical member carried by the frame extending in a vertical position, a plurality of targets hinged to the cylindrical member with their free ends extended inwardly toward the center thereof, said targets being disposed as the radii of the cylindrical member, means for locking each target in radial relation, slidable means disposed in the rear to receive the inclined targets, and means for sliding the same to reset the targets.

4. An amusement device, including a vertically disposed cylindrical support, a ring mounted forwardly of said support, the support and ring having their centers in the same axial line, a pad carried by said ring, a plurality of targets hingedly connected to the cylindrical support, said targets being disposed to form the radii thereof, resilient means for locking the same in radial relation to the cylindrical support, and slidably mounted means disposed to the rear of the targets for receiving the same when inclined and for resetting the same in radial relation to the cylindrical support.

5. An amusement device, including a vertically disposed cylindrical support, a ring mounted forwardly of said support, the support and ring having their centers in the same axial line, a pad carried by said ring, a plurality of targets hingedly connected to the cylindrical support, said targets being disposed to form the radii thereof, resilient means for locking the same in radial relation to the cylindrical support, a bar slidably mounted in the rear of the cylindrical support, a post carried by the bar, and a target resetting ring connected to the post and disposed to receive the inclined targets.

In testimony that I claim the foregoing as my own, I have hereto affixed my signature in the presence of two witnesses.

JOSEPH M. WEST.
